COMBINATION CAMP CHAIR AND ROCKER

Charles E. Meeker, Detroit, Mich.

Application May 27, 1933, Serial No. 673,139

2 Claims. (Cl. 155—56)

The present invention relates to improvements in camp chairs and provides a device of this character embodying a combination reclining chair and rocker that is collapsible so that it may be packed into a small compact bundle for various transportation purposes.

Another advantage of the invention is that it is very durable and when dismantled and repacked for storage or otherwise, the space required is so small that a number of the chairs may be stored in a comparatively limited space, consequently a quantity sufficient for camping purposes may be likewise carried within the automobile or other means of transportation.

With reference to the drawing:

Figure 1 is a perspective view of the complete invention normally ready for use.

Figure 2 is a fragmentary view of the cloth supporting members with said cloth being indicated by dotted lines, and broken as shown.

Figure 3 is a view showing one unit of the chair supporting members ready to be packed.

Figure 4 is an enlarged transverse section view of one of the chair supporting members showing the pivotal connection with the lower connecting bar.

Figure 5 is a sectional view of one of the chair supporting members, indicating the upper chain hook arrangement.

Figure 6 is a similar view of said member showing the lower chain hook arrangement.

Figure 7 is a view indicating how the complete device will appear when dismantled and packed.

Figure 8 is a sectional view of a modified form of a portion of the chair supporting members making a collapsible stationary chair.

The invention comprises a long frame unit having long standards 1 and 1A, and a short frame unit having short standards 2 respectively. One end of all of said standards being tapered as at 3 and 3A respectively, and the ends 3 being adapted to detachably engage similar tapered socket 4 of tubular member 5, and likewise ends 3A being adapted to detachably engage similar tapered socket 6 of tubular member 7, and with reference to Figure 2 it is clearly observed that both ends of members 5 and 7 are split as at 8 and are accordingly welded to the respective sockets 4 and 6 as indicated, and which provides a light weight, and very substantial form of construction for said members.

Referring to Figure 1 it is observed that cloth 9 is employed, which provides the seat and back

for the chair and may be of preferably a suitable canvas, or of any cloth material adapted for the purpose. Said cloth having pocket 10 stitched thereon and which is of adequate proportion to admit of member 5 to pass therethrough with the cloth being supported as indicated in this view. Similar pocket 11 is also stitched upon said cloth and is similarly related to member 7 as indicated.

The lower end of standards 1 and 1A are cut as at 12 in order that the chair will stand upon the floor normally as shown in Figure 1, and while not indicated in the drawing it is to be understood that a metal ferrule may be used for each of the ends 3 and 3A, if preferred.

In order to accomplish the rocking feature of the device, standards 1 and 2 are not adapted to be pivoted relative to each other, on the contrary, chains 13 are provided, one being for each chair supporting unit and one end of said chains being adapted to detachably engage hook 14, which is secured to standards 1 and 1A respectively, and the opposite end of said chains being permanently secured to lug 15 upon sockets 6 of member 7 as indicated. The manner in which hook 14 is secured to respective standards 1 and 1A is clearly shown in Figure 5.

In this position standards 1, 1A and 2 are supported at their lower end 12 by the respective chains 16, one end of which is permanently secured to standard 1 by connection 17 thereon and the opposite end of said chain being permanently secured to connection 18 upon standard 2, and it is understood that standards 1 and 2 remain permanently engaged as a single unit and being dismantled in this manner as indicated in Figure 3. It is further understood that there are two complete units of this character required for the chair. Connections 17 and 18 are clearly shown in Figure 6.

The lower end portions of standards 1 and 1A are rigidly reinforced when the chair is assembled and ready for use, by virtue of bar 19, one end of which is deflected as at 20, and adapted to pivotally engage a transversely arranged passage in standard 1 and forming head 21 with washer 22, as clearly indicated in Figure 4. The opposite end of bar 19 is deflected similar to end 20, and adapted to detachably engage aperture 23 in standard 1A.

With particular reference to Figure 8 a modified form of construction is shown. In this construction the chair is made stationary with standards 1 and 2 being pivotally engaged at the position of A in Figure 1, by virtue of rivet or

bolt B with washers C as indicated. In the stationary construction just described the chair becomes collapsible, identically as in the major construction.

- 5 Again referring to Figure 1, in the act of dismantling the chair, the end opposite the pivoted end of bar 19 is detached from standard 1A, chains 13 are detached from hooks 14, members 5 and 7 are likewise disengaged from standards 1, 10 1A and 2 respectively, with cloth 9 remaining upon said members. The elements are then rolled within said cloth and by means of strap 24 or any suitable cord, the chair presents a neat compact bundle as indicated in Figure 7.
- 15 Having thus described my invention, what I claim as new is:
1. An oscillating chair comprising a long frame unit and a short frame unit in crossed diagonal relation, said long frame unit comprising a pair 20 of side standards and means detachably connecting the upper ends of said standards and a brace bar connecting the lower ends of said side standards, said brace bar having a pivotal connection with one of said long frame standards and 25 detachably connected to the other of said long frame standards, said short frame unit comprising a pair of short side standards and means detachably connecting the upper ends of the same, flexible means connecting the lower ends of the 30

side standards of said frame units at each side of the chair, other flexible means connecting the upper ends of each short standard to an intermediate portion of a corresponding long standard, and a fabric seat and back member suspended between the means detachably connecting the upper ends of the side standards of each frame unit, said means detachably connecting the upper ends of the standards of each frame unit comprising a tie bar having tapered sockets at each end thereof and extending transversely of the bar, the upper ends of said standards being tapered and engaged in said sockets.

2. In an oscillating chair of the type comprising a long frame unit and a short frame unit in diagonal crossed relation and means interconnecting the frame units whereby said units may oscillate within limits relative to each other and in which each frame unit comprises a side standard at each side of the chair and a tie bar connecting the upper ends of the side standards and a fabric seat and back member hung between said tie bars, the provision of tapered sockets at each end of each of said tie bars and the further provision of a tapered end portion at 100 the upper end of each of said standards engaged in a socket of the corresponding tie bar.

CHARLES E. MEEKER.
